(57) **CLAIM**

The ornamental design for a phonograph, as shown and described.

DESCRIPTION

FIG. 1 is a front, right side, top perspective view of a phonograph showing my new design;

FIG. 2 is a rear left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view thereof with the lid in fully closed position.

The broken lines immediately adjacent to the claimed portions are boundaries, all other broken lines are environmental structures; all the broken lines form no part of the claimed design.
